TANK CAR UNDERFRAME STRUCTURE

Daniel C. Prescott, Granite City, Ill., assignor to
General Steel Castings Corporation, Granite
City, Ill., a corporation of Delaware

Application November 12, 1932, Serial No. 642,402

10 Claims. (Cl. 105—418)

This invention relates to railway rolling stock and consists in a novel underframe structure for tank cars.

Heretofore, certain grains and granular materials such as wheat, corn, cement, lime, sulphur, etc., which must be kept free from moisture and other impurities, have of necessity been shipped either in packages or in paper-lined box cars. The packaging of such materials obviously involves substantial labor expense, as does the lining of cars necessary for bulk shipment, and also bulk shipment in cars gives rise to dust waste and inconvenience and substantially increases the time required for loading and unloading. In the case of certain poisonous materials such as quicklime and arsenic, the more expensive packaging method of shipment must necessarily be resorted to at present due to the danger of exposing workmen to the free materials and the dust arising therefrom.

In order to provide dust and moisture proof shipment of such granular materials as referred to above, while at the same time expediting loading operations, the use of especially designed tank cars has been suggested, these being provided with conveyors to facilitate unloading through one or more hopper openings in the bottom.

The main object of the present invention is to provide a novel tank car underframe structure especially adapted for shipment of dry material.

Another object is to provide an underframe of the above type preferably comprising an integral cast metal unit which shall be simpler of assembly and more rigid and durable than ordinary built-up underframes at present in use.

Another object is to provide a tank car underframe structure including a center sill shaped to serve as a conveyor trough.

These objects and others hereafter appearing are attained substantially by the structure illustrated in the accompanying drawings in which—

Figure 1 is in part a side elevation of a tank car illustrating the invention and in part a vertical longitudinal section taken on the line 1—1 of Figure 2.

Figure 2 is a top view of the car, the left half showing the underframe only and the right half showing the tank sheets, running boards and other superstructure equipment applied thereto.

Figures 3 and 4 are vertical transverse sectional views taken on the corresponding section lines of Figure 1.

Figure 5 is an end view of the underframe.

Figure 6 is a vertical transverse section taken on the line 6—6 of Figure 2.

Figure 7 is a detailed section taken on the line 7—7 of Figure 2.

The main portion of the underframe is a cast metal structure having downwardly converging flat plates 1 terminating in a U-shaped trough structure 2 constituting a main center sill member extending substantially from end to end of the underframe. The sides of the center sill are braced at intervals by transverse ribs 5. The bottom wall of the center sill slopes upwardly from the center of the car towards each end and forms the top wall of the bolster structure indicated generally at 4 (see Figure 6). Downward extensions 3 of the sides of the center sill form draft sills extending from the end of the underframe to a point substantially spaced rearwardly of the bolsters and the bolster arms project outwardly from the center and draft sill elements. Upright webs 27 connect the bolster arms with the inclined walls 1. The bolsters include integral jacking plates 4a and center plates 4b. A central hopper 30 grooved at 31 for a closure member provides for discharge of the tank load.

The transverse bracing ribs 5 each has substantial cored openings 6 to lighten the structure and each has its bottom edge 6a spaced substantially from the bottom wall of the center sill to provide for the passage of conveyor mechanism thereunder. The side plates are preferably corrugated, as illustrated in Figure 7, the corrugations stiffening the plates and being disposed in a manner to conduct loaded material towards the center sill. The side plates extend around the ends of the underframe to form portions 1 of the tank ends.

The tank superstructure side sheets 8 and end sheets 9 are secured to the curved upper edges of the side plates 1 and end members 7 by rivets or welding, and plates 1 may be curved to conform with the contour of a cylindrical tank. The structure is further reinforced at the end by bands 29 extending from the extremities of the bolsters and up over the top of the car. At the top of the tank are provided a plurality of manways 10 for loading material into the car and at the center is a dome 11 for housing a conveyor mechanism motor and gearing. The manways and dome are provided with suitable covers 12 and 13.

The conveyor mechanism comprises a pair of endless chains or belts, indicated at 14, which pass over sprockets 15, 16, 17 and 18. Sprockets 15 are driven by a motor in dome 13 or from an

external source of power applied through suitable shafting. The portions of chains or belts 14 between sprockets 17 and 18 travel along the bottom of trough shaped center sill 2 and serve to carry loaded material to the center hopper 30. Each of the sprockets is located in position for convenient inspection, the outer sprockets 16 and 17 being mounted in housings 32 at the end of the car, the lower portions of which are formed by pockets 19 projecting from the end member 7 of the underframe and provided with perforated bearing bosses 25 for mounting the sprocket shafts. The central lower sprockets 18 are carried by stub shafts 20 mounted in bearing brackets 21 shown as formed integral with side walls of the center sill above the hopper 30.

Various other elements may be conveniently formed integral with the underframe, such as the running board brackets 22, air brake reservoir bracket 23, brake cylinder bracket 24, and hand brake bracket 26. Secured to the tank side sheets are suitable brackets 27a mounting additional running boards 28 to facilitate access to the manways and center dome.

The one-piece construction of the underframe eliminates labor and expense of machining and assembling various parts and also provides an underframe which is stronger and more durable than a built-up structure. Another important advantage of the one-piece construction is the elimination of crevices between joined members into which granular materials may sift and which eventually would become loose and impair the usefulness of the vehicle. The one-piece construction also permits the disposition of metal in such a way as to provide the greatest strength with the minimum amount of metal. In particular, the center sill may be made of suitable hollow construction to serve as a conveyor trough since underframe forces are distributed throughout the side plates 1 as well as the center sill. The bolsters 4 and ribs 27 extend a substantial distance upwardly along the side plates and reinforce the same.

Various details of the structure illustrated are not essential, such, for instance, as the shaping of the side plates 1 and the center sill trough, the conveyor mechanism used and the arrangement of the loading openings, and these may be varied without departing from the spirit of the invention and exclusive use of all such modifications as come within the scope of the appended claims is contemplated.

What is claimed is:

1. A railway vehicle trough-shaped center sill arranged to extend from end to end of the vehicle underframe, the transverse web of said sill sloping smoothly downwardly from the ends towards a center outlet opening and said sill having bearings for mounting conveyor mechanisms.
2. A tank car integral cast metal underframe structure including upwardly and outwardly sharply sloping side plates of substantial depth, and a trough-shaped center sill connecting the lower extremities of said plates, said plates merging with each other at the ends to form substan-

tial portions of the tank end members and the lower portions of said end members forming the ends of the transverse web of said sill.

3. In a railway vehicle, superstructure including a conveyor mechanism pocket projecting from the end wall thereof, and an integral underframe structure including a conveyor trough and side plates forming portions of the car bottom, said side plates merging at the ends to form substantial portions of the superstructure end wall and being bulged outwardly to form continuations of said pocket.

4. In a car for transporting granular materials in bulk, a conveyor trough having an outlet opening, and substantially flat side plates sloping upwardly and outwardly from said trough, said plates and trough extending from end to end of the car body and forming the car underframe for transmitting longitudinal forces.

5. In a tank car, a continuous thickness of metal forming the tank bottom and also forming the car center sill, said metal having an open trough-shaped part and bolster structure extending beneath and outwardly from the sides of said part.

6. In a tank car, a continuous thickness of metal forming the tank bottom and also forming the main longitudinal member of the car underframe, said metal including a longitudinal trough-shaped portion extending from end to end of the underframe, and bolster structure extending beneath said trough-shaped portion and having top wall elements formed in part by the bottom wall of said trough-shaped portion.

7. In a tank car, a continuous thickness of metal forming the tank bottom and also forming the main longitudinal force transmitting member of the car underframe, and bolster structure depending from said metal and spaced from the ends of the car, said metal including an open trough extending longitudinally therealong and passing through said bolster structure.

8. In a railway car underframe, a trough-like member forming the main longitudinal member of the underframe and the bottom of a tank structure, and bolster arms projecting outwardly from the upright sides of said member intermediate its ends.

9. In a railway car, tank structure, a deep trough in the bottom thereof and extending smoothly from end to end thereof, and bolster structure including arms extending outwardly from the sides of said trough, there being a conveyor mechanism operating in said trough below the level of the top of said bolster structure.

10. A tank car underframe structure including a hollow center sill forming a conveyor trough, side plates sloping outwardly and upwardly from said sill for directing lading material thereinto, and other plates merging with said side plates and extending around the end of the underframe to form part of the car end wall and bulged outwardly in line with said center sill for accommodating conveyor mechanism.

DANIEL C. PRESCOTT.
